Bridgeport, Conn., assignors to General Electric Com-
pany, a corporation of New York

Filed Jan. 17, 1961, Ser. No. 63,590

Term of patent 14 years

(Cl. D58—12.6)

Fig. 1.

Fig. 2.

Fig. 3.

FIG. 4.

FIG. 5.

FIG. 1 is a front perspective view of a display box for a clock embodying my new design, a portion of the transparent cover being broken away to show the nature of the structure under the transparent cover;

FIG. 2 is a front elevational view of the display box for a clock shown in FIG. 1;

FIG. 3 is a top plan view of the display box for a clock shown in FIG. 1;

FIG. 4 is a rear elevational view of the display box for a clock shown in FIG. 1; and

FIG. 5 is a side elevational view of the display box for a clock shown in FIG. 1.

It is understood that the cross-hatched ornamentation in FIGS. 2 and 3 is continued over the area as shown in FIG. 1.

We claim:

The ornamental design for a display box for a clock or the like, substantially as shown and described.
